US00D852408S

(12) **United States Design Patent** (10) Patent No.: **US D852,408 S**
 Nettенstrom et al. (45) Date of Patent: ** Jun. 25, 2019

(54) **ELECTRONIC CIGARETTE**

(71) Applicant: **Nicoventures Holdings Limited**,
 London (GB)

(72) Inventors: **Matthew Joel Nettенstrom**, Oakbrook
 Terrace, IL (US); **Steven Michael
 Schennum**, Oakbrook Terrace, IL (US);
Thomas Michael McKeon, Oakbrook
 Terrace, IL (US); **Justin Banker Peart**,
 Oakbrook Terrace, IL (US); **Jeremy
 Wright**, London (GB)

(73) Assignee: **NICOVENTURES HOLDINGS
 LIMITED**, London (GB)

(**) Term: **15 Years**

(21) Appl. No.: **29/573,612**

(22) Filed: **Aug. 8, 2016**

(30) **Foreign Application Priority Data**

Feb. 8, 2016 (EM) 002978197

(51) LOC (11) Cl. **27-01**
